UNITED STATES PATENT OFFICE

HAROLD L. HAYNES, OF WEST CHICAGO, ILLINOIS

TIME-CONTROLLED ELECTRIC SWITCH

Application filed February 18, 1928. Serial No. 255,213.

The present invention relates to electric switches and to a timing mechanism whereby they can be actuated automatically at definite and variable intervals.

5 One of the objects of the invention is to provide an improved form of actuating mechanism capable of use with a snap switch or the like; which mechanism is clock-driven and bears a very simple mechanical relationship with the switch itself.

Another object of the invention is to provide a housing comprising two separable halves; one of which halves contains the switch itself and all of its associated mechanism, conducting wires, etc.; the other of which halves contains all of the time-operated mechanism which actuates the switch at definite controllable intervals.

Another object of the invention is so to 20 construct the switch and the time-controlled mechanism associated therewith that it becomes possible to remove entirely the time-controlled mechanism together with the portion of the housing that it occupies, and to 25 replace it by another like mechanism also contained in a similar housing, for purposes of substitution or repair.

Another object of the invention is to provide a time-controlled mechanism that, while 30 engaging the levers of a snap-switch, is otherwise entirely disconnected from the switch.

Other objects will appear in connection 35 with the description and drawings which form part of this specification.

In the drawings:

Figure 1 is a front elevational view of the improved time-controlled element within its housing;

Fig. 2 is a side elevation, with part of 40 the housing cut away to show the interengagement of the time-controlled mechanism with the switch;

Fig. 3 is a rear view of the forward half 45 of the housing showing the therein contained time-operated mechanism; and

Fig. 4 is a front view of the switch in its particular portion of the housing.

The entire device, made in accordance with 50 the present invention, comprises two separable housings 10 and 11, so constructed as to

allow them to be attached to each other to form a complete unitary housing for both the time-controlled mechanism and the switch. As shown in the drawings, housing 10 holds the time-mechanism, which may take 55 the form of a clock, and will be so referred to hereinafter, and housing 11 holds the switch proper.

Referring to Figs. 1 and 2, it will be seen that the housing 10 has a hinged door 12 at 60 its forward side. This door is provided with a glass or other transparent window 13 through which the time indicating and control-indicating hands, dials, etc. are visible. Means for tightly closing the door 12, as for 65 instance by a screw 14, are provided; and preferably a gasket of waterproof and dust-proof material is placed between the door and the body of the housing 10 to prevent 70 access of dust and moisture.

The housing 10 is slightly smaller than the housing 11 and fits into a rabbeted edge of the latter, as may be seen in Fig. 2, thus forming a tight joint 15 between the two 75 housings. In order to fasten the housings together, the rearward housing 11 is provided with two forwardly projecting male screws 16 which extend almost to the forward interior surface of the housing 10. Suitable female screws 17, passing through 80 openings in the front surface of housing 10, engage the screws 16, and serve to hold the two housings and their therein contained mechanism in proper relationship. The screws 17, having solid slotted heads, effectively seal off the housing 10 against admission of dust and moisture.

It will thus be seen that the assembling of the two housings is an exceedingly simple 85 operation, and consists merely in placing the housing 10 into the rabbeted edge of the housing 11, thereby properly centering the screws 16 with the holes through which the screws 17 pass, and thereupon inserting and tightening the screws 17.

Referring for the moment to Fig. 4, which shows the rearward housing 11, this contains, fastened to its interior rear surface, a standard form of electrical snap-switch 21. Electrical conductors 22 connect the binding 120

posts and contacts 23 and 24 on the switch. These conductors pass out of the housing 11 through the conduit 18. If it be merely desired that the switch be in the "off" position when turned 90° about its pivot, then one set of wires may be left off. In the modification shown, the switch is in the "on" position relative to the conductors 23, but "off" as regards conductors 24. In place of the button or knob usually found on snap-switches, there is provided a double lever 25 which is keyed to the shaft 26 of the switch, so that on moving the lever 25 the shaft 26 will be rotated. It is also to be understood that there is the usual form of restraining spring within the switch so that the same will suddenly and rapidly change its position when the shaft 26 is turned about 40°, whereupon the switch mechanism will operate and throw the bridging contact 27 across the other set of contacts 24. All of this construction is, however, well known in the art of snap-switch construction and need therefore not be minutely described.

The one essential difference in the present switch is that the lever 25 replaces the ordinary knob. This lever, by reason of its shape, makes it possible to operate the switch by the controlling mechanism whose release is actuated by a clock in the housing 10.

Fig. 3 shows the housing 10 with the clock 30 fastened to the interior thereof by screws 31. This clock may be of standard construction, and may be similar to an alarm clock. Two sets of springs 32 and 33 in said clock operate the time-mechanism and the switch-turning mechanism, respectively. The switch-turning mechanism is driven by the spring 33, which through a suitable train of gears actuates the large gear 34. On the release of a trigger mechanism within the clock 30, the gear 34 will turn in the direction of the arrow thereon in Fig. 3. The gear 34, however, also carries two projecting lugs 35 (see both Figs. 2 and 3) rigidly fastened to its surface and of sufficient length to engage the arms of the lever 25 when the two housings are fitted together. As the gear rotates, the lugs 35 will contact with the sides of the lever 25 and will urge the same in a clock-wise direction. When the lever 25 and the shaft 26 keyed thereto have been turned about 40°, the spring within the switch 21 will throw the lever 25 the balance of the 90° that it is capable of moving, and thereupon the circuit thus bridged will be closed. The gear 34 however continues to revolve until the same has made a 90° turn, whereupon, by proper tripping mechanism in the clock, the gear will be brought to a stop.

This motion will be repeated the next time the trigger mechanism in the clock is released. The release of this trigger mechanism is effected by the contact of indicating hands 40 and 41 on the small dial 43 on the front side 65 of the clock, (as shown in Fig. 1) with a pro-

jecting arm 42. The exact arrangement of this release mechanism is not shown, as it, also, may be of standard type as is well known in the art of constructing alarm clocks and the like.

The hands 41 and 40 can be moved to any point on the dial 43. This dial, together with the hands thereon, rotates once in 24 hours; while the regular hour hand 44 makes two revolutions in 24 hours; and the minute hand 45, 24 revolutions. However, the minute and hour hands may be omitted, and are merely for the convenience of the person inspecting the clock to see if it is showing correct time.

The purpose of the two separate control hands 40 and 41 is to cause the switch-turning mechanism to be released twice in 24 hours; although obviously the interval between the release may be any desired one; and may take place oftener than stated. The important point is that the clock mechanism with its associated switch-turning gear 34 is housed by itself in the housing 10, while the switch is housed by itself in housing 11.

It thus becomes evident that there is provided, by the present invention, a simple and effective device for operating an electrical switch at predetermined intervals, and to do so automatically and without the necessity for personal supervision. If the clock be made to run a long time without winding, or even be electrically operated so as to obviate any winding at all, the switch may be operated for long periods of time at stated intervals without attention. However, if for any reason the clock mechanism becomes deranged, or if it is desired to substitute therefor a mechanism operating the switch at intervals different than those available with the particular clock mechanism in use, it suffices to release the screws 17 from the screws 16, and to replace the housing 10 with its clock by another similar housing containing a substitute clock of the same general type.

One application of the improved device provided by the present invention is for the operation of electrically illuminated signs along outlying country roads and the like. These signs are usually illuminated from a time slightly before darkness sets in, and until shortly after midnight; or even in some cases, all night long. The device herein described may be placed in circuit with the lighting system that illuminates the sign, and if the hand 40 be set for, say, 6 P. M., the clock mechanism will release the switch-turning mechanism at that time, and illuminate the sign. If the hand 41 be set for say 5 A. M., the continued rotatory movement of the dial 43 which turns with the hand 41 will eventually bring the hand 41 into contact with the release lever 42 whereupon the switch-turning mechanism will function again, this time turning off the illumination. Alternatively, this switch, while turning off

the illumination, may simultaneously turn on the current for some moving device on the sign which it might be desired to operate during day-light hours.

5 The clock and switch mechanism, all being housed in an air and moisture proof container, may be placed out of doors and at any convenient place, as on the front or back of the sign, and will continue to operate as long
 10 as the clock is kept running. Inspection at stated intervals, to wind the clock and oil the mechanism, is all that is needed. If the inspector is also provided with additional clock mechanisms already secured in housings
 15 properly proportioned so as to fit the switch-housings, any defective clocks can be replaced with a minimum of time and effort.

The housings 10 and 11 may be made of metal, or of molded material, and the exact
 20 methods of attaching the doors to the housing 10 are not important. Furthermore, the precise internal construction of the clock, the switch-turning mechanism, and the switch itself are also not important, and variations
 25 in such construction are to be considered as within the scope of the invention, which is to be construed in accordance with the hereunto appended claim, to wit:

A time-controlled switch construction comprising a housing, a snap switch operating member in said housing, rotatable step-by-step in the same direction to turn the switch on and off, a second housing, a time-controlled actuating member in said second housing, rotatable step-by-step in the same direction, and means for securing said housings together and so positioning them that said actuating member will be coaxial with said operating member, said actuating member having a lost-
 40 motion engagement with said operating member whereby said operating member may snap ahead of said actuating member to provide a snap action for the switch.

In witness whereof, I have hereunto sub-
 45 scribed my name.

HAROLD L. HAYNES.
